RESETTING MEANS FOR SAFETY SHUTOFF DEVICES

Paul L. Betz, Baltimore, Md., assignor to Consolidated Gas Electric Light and Power Company, Baltimore, Md., a corporation of Maryland

Application January 31, 1940, Serial No. 316,676

7 Claims. (Cl. 158—117.1)

This invention relates to resetting means for shut-off devices, and more particularly to resetting means for shut-off devices that are electromagnetically controlled.

In automatic systems for the operation of gas burners, it is necessary to have a pilot or ignition flame at or adjacent to the gas burner to insure proper ignition when burner operation is required. In such systems, safety devices are usually employed to prevent the flow of gas to the burner should the pilot or ignition flame be extinguished.

The safety device so used is referred to as a shut-off device and provides means independent of the burner control device for preventing the flow of gas to the burner. Safety shut-off devices may be installed in the gas supply line to the burner so that closure of the shut-off valve interrupts the flow of gas to the main burner only. In this case, gas for the pilot or ignition flame is supplied by a connection ahead of the shut-off device. Another method of installing the shut-off device is to make the gas connection for the pilot or ignition flame to the supply line after the shut-off, whereby closure of the shut-off device prevents the flow of gas to the pilot burner as well as to the main burner. This latter system is known as a complete shut-off system.

It is an object of this invention to provide a resetting means for shut-off devices so that when the shut-off valve has closed, resetting can be accomplished only if a proper ignition flame exists at the pilot burner.

A further object of the invention is to provide resetting means which permits the use of a shut-off device for complete shut-off of the burner system, and includes means for supplying gas to the pilot burner from the inlet side of the shut-off device during the resetting operation and from the outlet side of the shut-off device after the shut-off valve is open.

A further object of the invention is to provide a visual indication or means for operating an electric circuit including signaling means when the shut-off device operates.

Another object of the invention is to provide resetting means that is certain in operation, simple in construction and durable.

Other objects will appear as the description of the invention proceeds.

The invention is capable of receiving a variety of mechanical expressions one of which is illustrated on the accompanying drawing, but it is to be expressly understood that the drawing is

for purposes of illustration only, and is not intended as a definition of the invention, reference being had to the appended claims for that purpose.

5 Referring in detail to the accompanying drawing wherein the same reference characters are employed to designate corresponding parts in the several figures:

Fig. 1 is a diagrammatic elevation to illustrate an embodiment of the invention;

Fig. 2 is a vertical axial section of this embodiment on a larger scale;

Fig. 3 is a top plan view of the structure of Fig. 2; and

15 Fig. 4 is a cross-section on the line 4—4 of Fig. 2.

Referring to Fig. 1, the main gas burner is indicated at 1, and the conduit 2 is the fuel supply conduit therefor. For purposes of illustration, a shut-off device in the form of a valve of the thermoelectric type is indicated at 3, and is here shown as installed in conduit 2 between the gas supply and main burner 1. Associated with main burner 1 is a pilot or ignition burner 4 having a fuel supply conduit 5. A thermocouple is shown at 6 and is heated by the pilot or ignition flame from burner 4 to energize an electromagnet winding diagrammatically indicated at 7 (see Fig. 2). The arrangement shown in Fig. 1 is for complete shut-off and upon extinction of the flame at pilot burner 4 and subsequent closure of the valve or shut-off device 3, all gas flow is thereby interrupted.

Referring now to Fig. 2, the details of construction of a preferred embodiment of the invention are illustrated. The shut-off device is indicated at 3, having inlet and outlet chambers 8 and 9, respectively. Valve port 10 is interposed between chambers 8 and 9 so that the flow of gas

40 may be interrupted upon closure of valve member 11. A spring 12 is shown in Fig. 2 as biasing valve member 11 to its closed position. A valve stem 13 extends from said valve member and is attached to the armature 14 of an electromagnet,

45 so that when armature 14 is in the raised position indicated in Fig. 2, valve 11 is open and gas may flow between inlet and outlet chambers 8 and 9. Said electromagnet includes a U-shaped magnetizable element 15 having pole pieces co-operating with the armature 14. Electromagnet winding 7 may be connected to any suitable source of electromotive force, in the illustrated embodiment to a thermocouple 6 subjected to the pilot flame. The electromagnet winding 7 surrounds at least one leg of U-shaped element

50 55

15 and is stationarily mounted in any suitable way, while said U-shaped element 15 is freely movable with respect thereto in the direction of the axis of the winding. As shown in Fig. 2, U-shaped element 15 is mounted on or has attached thereto a cross member 16 which is urged upward, as viewed in the figure, by one or more springs 17 which together are stronger than spring 12. Stem 18 is attached to cross member 16 and passes through the casing of the shut-off device, and is provided with suitable packing to prevent the leakage of gas.

It is thus seen that when valve member 11 is in its closed position, armature 14 is normally separated from the pole pieces of U-shaped element 15 due to the combined action of springs 12 and 17. In order to open the valve and maintain the valve member in open position, it is first necessary to establish the pilot flame at burner 4 to supply heat to thermocouple 6 and thereby energize electromagnet winding 7. Manual movement of stem 18 downward as viewed in Fig. 2 causes U-shaped element 15 to be moved toward armature 14 until contact is established between the pole faces and the armature, in doing which springs 17 are compressed, and if electromagnet winding 7 is now receiving sufficient energy from thermocouple 6, armature 14 will be held to the pole faces of element 15, and upon release of stem 18 the springs 17 will move element 15, armature 14, valve stem 18 and valve member 11 upward against the force exerted by spring 12, thereby opening the port 10 between chambers 8 and 9. In doing this, valve spring 12 is compressed so that upon cooling of thermocouple 6 and deenergization of winding 7, armature 14 will be moved away from the pole faces of element 15, thereby permitting valve 11 to close.

The description given so far of Fig. 2 covers a resetting means suitable for a safety shut-off device when used where interruption of the gas flow to the main burner only is required. In this case, the conduit 5 to pilot burner 4 may be connected to conduit 2 on the inlet side of the safety shut-off device, or may be tapped directly into casing 3 into chamber 8.

Where complete shut-off is required, the resetting means described so far is necessary together with a valving arrangement interlocked with the operation of stem 18. For this function, any suitable valving arrangement may be employed, but for the purposes of exemplification, a 3-way plug cock is illustrated. This 3-way plug cock comprises a movable plug 23 which fits a stationary housing member provided with three port connections, 20, 22 and 21. Plug 23 is provided with two passages one of which is indicated at 21a and the other of which is indicated at 21b (Fig. 4). Passage 21a provides a path for the flow of gas from port 21 to port 22, and when plug 23 is moved away from the position shown in the drawing, this path for the gas is interrupted and another path is established from port 20 to port 22 by means of the passage 21b. Port 21, designated "To outlet," communicates with a conduit 27 leading to the outlet side 9 of valve 3. Port 20, designated "To inlet," communicates with a conduit 21a leading to the inlet side 8 of valve 3. Port 22, designated "To pilot" is connected to the fuel supply conduit 5 leading to pilot burner 4. Thus said plug cock provides, in one position of plug 23, for the flow of gas from the inlet side of valve 3 through conduit 27a, port 20, passage 21b to port 22, conduit 75

5 and pilot burner 4, and in the other position of plug 23 for the flow of gas from the outlet side of valve 3 through conduit 27, port 21, passage 21a to port 22, conduit 5 and pilot burner 4.

5 Referring to Fig. 2, movement of plug 23 is accomplished by means of a lever 24 which is suitably attached to the extremities of tapered plug 23, as by screws 25, and which has an extension 26 which projects over the outer extremity 10 of stem 18. When valve 11 is closed, lever 24 may be depressed manually and extension 26 engages stem 18 to move the pole pieces of U-shaped element 15 into contact with armature 14. This movement of lever 24 causes plug 23 to establish the flow of gas from the inlet side 8 of valve 3 through port 20 to port 22, conduit 5 and pilot burner 4. While still holding lever 24 in this depressed position, it is now possible to light the pilot flame at burner 4, which causes thermocouple 6 to be heated. When thermocouple 6 is heated sufficiently, electromagnet winding 7 will be energized and will cause armature 14 to adhere to the pole pieces of element 15. Upon releasing lever 26, plug 23 may move to the position shown in Fig. 2 under the action of a spring or springs (not shown), and springs 17 will cause valve member 11, armature 14 and element 15 to move upwardly as viewed in the figure, spring 12 being compressed, and stem 18 assuring movement of lever 24 to its position for connecting the outlet side 9 of the shut-off device with the pilot burner. The movement of tapered plug 23 from its manually maintained position to its normal or steady running position shown in Fig. 2 interrupts the flow of gas to burner 4 from the inlet side of the shut-off device by way of port 20, and establishes the flow of gas to pilot burner 4 from the outlet side 9 of the shut-off device by means of conduit 27, port 21, passage 21a, port 22 and conduit 5 to pilot burner 4.

Should the pilot flame at burner 4 be extinguished, thermocouple 6 will cool and electromagnet winding 7 will be deenergized. U-shaped magnetizable element 15 can then no longer hold armature 14 by magnetic attraction against the action of spring 12, and these members will separate causing valve member 11 to close port 10. Inasmuch as the gas flow from port 22 to pilot burner 4 comes from the outlet side 9 of shut-off device 3, closure of valve 11 interrupts the flow of gas to both the main burner 1 and the pilot burner 4.

Considering Fig. 2, it will be seen that in the steady running position there shown, the action of springs 17 is upward and opposite to that of spring 12, and when armature 14 is released from the pole pieces of element 15, upon deenergizing electromagnet winding 7, the opposing effect of spring 12 is reduced and springs 17 may then produce an additional outward movement of stem 18. Thus closure of valve member 11 may be indicated visually outside the valve casing by a change in position of stem 18, or if desired, the additional movement of stem 18 upon its release and closure of valve 11 may be utilized to operate electrical contacts in any suitable circuit to operate signal or other devices therein, as indicated diagrammatically by the leads 28. or the movement of stem 18 may be used to operate any suitable switch or contact device, as for example a mercury tube type switch.

From the above, it is seen that the present invention provides a resetting means for safety shut-off devices where the devices are used for either the complete or the partial shut-off of

the gas supply. In addition, visual indication is given, or electrical means may be operated, upon closure of the valve of the shut-off device. The above description has been given for a thermoelectrically operated shut-off device, but as will be obvious to those skilled in the art this is for purposes of illustration only, as any other suitable type of energization of the electromagnet may be employed and similar results will be obtained. Other forms of safety control devices may be used, and changes may also be made in the form of the valve 11 or the plug cock, as well as in other details of construction, arrangement, proportion, etc., of parts without departing from the spirit of the invention. Reference is therefore to be had to the appended claims for a definition of the invention.

What is claimed is:

1. In a safety control device of the type employing an electromagnet for holding the device in open position and requiring manual resetting to open position, the combination of an armature connected to a controlling member, resilient means for biasing said armature and controlling member to closed position, a movable U-shaped magnetizable element having pole pieces cooperating with said armature, a stationary electromagnet winding surrounding at least one leg of said element and arranged to permit the free movement of said element therethrough, said winding being adapted when energized to cause said element to hold the armature and the controlling member in open position, resilient means stronger than said first-named resilient means for biasing said U-shaped element together with said armature to open position, said second-named resilient means acting in opposition to said first-named resilient means and operating to hold said first-named resilient means under compression when said armature is holding the controlling member in open position, and resetting means for manually moving said pole pieces into engagement with said armature when said armature is in the closed position of said controlling member against the action of said last-named resilient means, whereby upon resetting said pole pieces may be moved manually into engagement with said armature and upon the manual release of said resetting means said U-shaped element, armature and controlling member may be moved to open position by said last-named resilient means provided said winding is properly energized.

2. In a safety control device for gas valves of the type employing an electromagnet for holding the valve in open position and requiring manual resetting to return the valve to open position, the combination of an armature connected to the valve, a movable U-shaped magnetizable element having pole pieces cooperating with said armature, a stationary electromagnet winding surrounding at least one leg of said element and arranged to permit the free movement of said element therethrough, said winding when energized being adapted to hold said armature and element in engagement and said valve open, resilient means for closing said valve upon de-energization of said winding, a manual resetting device for resetting said valve to open position, said resetting device comprising resilient means stronger than said first-named resilient means and acting in opposition thereto for biasing said U-shaped element together with its armature against the tension of said first-named resilient means to the open position of the valve, means

for manually moving said U-shaped element into contact with said armature when the armature and the valve associated therewith are in the closed position of the valve, and a flow-control-

5 10 15 20 25 30 35 40 45 50 55 60 65 70 75

device for connecting a pilot burner to the inlet side of said valve when said U-shaped element is manually moved into contact with said armature when the valve is closed, said second-named resilient means, upon movement of said armature and U-shaped element to the open position of said valve, cooperating with said flow-controlling device to assure that said pilot burner is connected to the outlet side of said valve.

3. In a safety control device of the type employing an electromagnet for holding the device in open position and requiring manual resetting to open position, the combination of an armature connected to a controlling member, a stationary electromagnetic winding, a magnetizable element associated with said winding to provide the poles of an electromagnet and cooperating with said armature, said element being adapted to move with respect to said winding in the direction of the axis thereof, said winding being adapted when energized to cause said element to hold said armature in contact therewith, resilient means for biasing said controlling means toward closed position, and a second and stronger resilient means for biasing said element in the opposite direction, said second resilient means acting in opposition to said first resilient means to move said armature and controlling member therewith to open position and hold said first resilient means under compression when said winding is energized.

4. In a safety control device for gas valves of the type employing an electromagnet for holding the valve in open position and requiring manual resetting to return the valve to open position, the combination of an armature operatively connected to the valve, a stationary electromagnetic winding, a magnetizable element associated with said winding to provide an electromagnet and cooperating with said armature, said element being adapted to move with respect to said winding in the direction of the axis thereof, resilient means for moving said valve to closed position when said armature is released from said element, and a second and stronger resilient means cooperating with said element for moving said element in the opposite direction to move said armature and valve therewith to open position and compress said first-named resilient means when said winding is energized.

5. A device according to claim 4 which also includes a valve for controlling the flow of gas to said pilot burner from either the inlet or the outlet side of said first-named valve, and said second-named resilient means cooperating with said last-named valve for holding said last-named valve in its position for admitting gas to said pilot burner from only the outlet side of said main valve.

6. A device according to claim 4 which also includes a valve for controlling the flow of gas to said pilot burner from either the inlet or the outlet side of said first-named valve, and manually operable means associated with said last-named valve and cooperating with said element for moving said element into contact with said armature, said last-named means establishing communication between said pilot burner and the inlet side of said first-named valve only when said element is being manually held against the tension of said stronger resilient means.

7. A device according to claim 4 which also includes a valve for controlling the flow of gas to said pilot burner from either the inlet or the outlet side of said first-named valve, means associated with said element and with said second-named valve whereby said second-named valve is in one or the other of its positions depending upon whether said element is moved into engagement with said armature against the

5 tension of said second-named resilient means or held in its opposite position by said second-named resilient means, and means actuated by the movement of said element under the action of said second-named resilient means when said armature is separated from said element by said first-named resilient means for indicating when said first named valve is closed.
